UNITED STATES PATENT OFFICE

BENJAMIN R. HARRIS, OF CHICAGO, ILLINOIS

ENVELOPE

Application filed June 13, 1924. Serial No. 719,710.

This invention relates to envelopes, and has for its object to provide a new and improved device of this description.

One of the objects of the invention is to so 5 treat the envelope or the paper used for the manufacture of the envelope chemically or mechanically or both, so that the opening of a letter received in the mails is simplified, and so that danger of accidental tearing of the in- 10 closed documents are prevented.

The invention has a further object to provide an envelope that shows a tear after the sealed envelope has once been opened.

The invention has further objects which are 15 more particularly pointed out in the accompanying descriptions.

Referring now to the accompanying drawing,

Fig. 1 is a view of one form of envelope 20 embodying the invention.

Fig. 2 is a view showing the envelope before the parts are folded.

Fig. 3 is a view showing a modified construction.

Fig. 4 is a view showing a further modified construction.

Referring now to the drawings, I have shown in Fig. 1 an envelope embodying the invention sealed ready to be opened by the receiver. The envelope is made in the ordinary way from a blank having the top and bottom folds 1 and 2, the end pieces or folds 3 and 4 attached to the central portion 5, such envelope being shown in Fig. 2 before it is 30 folded into the position shown in Fig. 1, the top and bottom and end pieces being folded over to complete the envelope.

In carrying out my invention I weaken the material of the envelope at a certain point 40 or points so that when the envelope is opened the material will be torn at the weakened point or points. I may weaken this material either chemically or mechanically.

In carrying out my invention I apply an adhesive 6 to the edge 7, 8 of the fold 2. I 45 also apply adhesive 9 to the edge 10 and 11 of the fold 1 and along a portion of the edge 11, 12 of the fold 1, leaving a portion of such edge free from adhesive material. The fold 50 2 or the fold 3 is weakened at the edge in

any desired manner, as, for example, by the application of some suitable chemical such as acid or alkali or an acid salt or a combination of a suitable acid with a salt. This weakening chemical is applied to a suitable 55 area along the edge 7, 13 of the fold 2, such for example, as the area 14. I prefer to have a short space between the edge and the area 14 free from the weakening chemical. Any suitable chemical may be used, such for ex- 60 ample, as hydrochloric acid, perchloric acid, hydrochloric acid with a moderate amount of zinc chloride, or sodium or potassium hydroxide solution or sulphuric acid or any other weakening chemical. The chemical is 65 properly diluted so as not to destroy the material of the envelope, but simply weakens it. I have found, for example, that a 37 per cent hydrochloric acid or a 5 to 10 per cent perchloric acid or a 1/2 to 4 per cent sodium 70 of potassium hydroxide or sulphuric acid will secure good results. Any of the usual adhesives may be used, such as ordinary envelope glue, casein glue, resin gum or rubber cements and the like.

Location of the weakened part 14 may, of course, be varied, but I prefer to have it somewhere near the middle of the edge 7, 13 of the fold 2. Instead of using a chemical to weaken the material of the envelope I may 75 weaken it mechanically, as for example, by removing a portion of the material by forming a slot, a series of perforations or the like.

In Fig. 2 I have shown the fold 3 provided with a slot 15. Instead of using a simple slot, as shown in Fig. 2 I may use any other weakening construction. I have shown two other forms, namely, the form 16 of Fig. 3 and 17 of Fig. 4. In each case the adhesive is applied preferably in the process of manufacture of the envelope to a portion of the fold in proximity to the weakened portion, or on the fold which is engaged by the fold having the weakened portion. In Fig. 2 I have shown the fold 3 as being provided with 85 the adhesive 18 near its edge, and this adhesive will be used if there is no mechanical weakening of the fold 3, but said fold 3 or the fold 2 is chemically weakened.

In Fig. 3 I have shown the adhesive 19, in 100

Fig. 4 adhesive 20. The adhesive 18 to 20 is preferably placed on the outside of the material of the envelope. The sender moistens the adhesive area 18, 19 or 20 and 5 presses the fold 2 down upon it, the fold 3 being folded over on the central portion 5, and then seals the fold 1 in the usual manner. When the receiver receives the envelope he 10 opens it by inserting a finger or any other opening device between the folds 2 and 3 at 21, Fig. 1 and forces his finger toward the fold 1. This causes a tear in the fold 3 or 2 depending upon which is weakened, and 15 the envelope is thus easily and quickly opened without any danger of tearing the documents as is often done when the envelope is opened in the usual way by an opener which cuts or tears the edge 22, Fig. 1.

It will also be seen that the envelope shows 20 positive evidence that it has been opened, such evidence being the tear in the fold 2 or 3.

It will be noted that the portions of the envelope that are weakened are on the diagonally extending edge either of the side fold or 25 the end fold and that the envelope is not opened at the top as is usually done but is opened along the adjacent diagonally extending edges; that is, the opening device, either the finger or anything used for this purpose, 30 is inserted as clearly shown in Fig 1 at the point 21 where these diagonally extending edges meet.

I claim:

1. An envelope adapted to be closed at one 35 point and opened at another point comprising a central portion, two side folds and two end folds folded thereon to form the complete envelope, one of said side folds being the closing point and one of said end folds being 40 the opening point, the material near the edge of said end fold being weakened, a portion of such edge being free from adhesive material, another portion of the edge being connected by adhesive material to one of the 45 side folds whereby, when an opening device is inserted between the side fold and the end fold the material near the edge of which is weakened, to open the envelope, the material of the end fold is torn.
2. An envelope in which the enclosure is 50 inserted at one side and removed from the other end, comprising a central portion having two side folds and two end folds adapted to be folded on the central portion so as to 55 provide edges extending diagonally across the envelope, means for fastening all of said folds together permanently when the envelope is sealed, one of the end folds being weakened along its diagonally extending 60 edge so as to tear when an opening device is inserted between the said weakened end fold and the adjacent side fold.

Signed at Chicago, county of Cook, and State of Illinois, this 28th day of May, 1924.

BENJAMIN R. HARRIS.
